(57) **CLAIM**

The ornamental design for a bicycle storage container, as shown and described.

DESCRIPTION

FIG. 1 is a perspective elevation view of an illustrated embodiment of a bicycle storage container showing the new design;

FIG. 2 is a front side view thereof;

FIG. 3 is a rear side view thereof;

FIG. 4 is a top view thereof;

FIG. 5 is bottom view thereof;

FIG. 6 is a left side view thereof;

FIG. 7 is a right side view thereof; and,

FIG. 8 is an elevation view of the bicycle storage container shown in context with front side and left side views visible. The broken lines in the figures are directed to environment forming no part of the claimed design or show portions of the bicycle storage container that form no part of the claimed design.

The shade lines in the figures show contour and do not claim surface ornamentation or treatment.
